(57) **CLAIM**

The ornamental design for a vapor distributor, as shown and described.

DESCRIPTION

FIG. 1 is a perspective view of a first embodiment of the vapor distributor showing my new design.

FIG. 2 is a front elevation view thereof.

FIG. 3 is a top plan view thereof.

FIG. 4 is a rear elevation view thereof.

FIG. 5 is a right side elevation view thereof.

FIG. 6 is a left side elevation view thereof.

FIG. 7 is a bottom view thereof. distributor showing my new design.

FIG. 8 is a perspective view of a second embodiment of the vapor distributor showing my new design.

FIG. 9 is a front elevation view thereof.

FIG. 10 is a top plan view thereof.

FIG. 11 is a rear elevation view thereof.

FIG. 12 is a right side elevation view thereof.

FIG. 13 is a left side elevation view thereof; and,

FIG. 14 is a bottom view thereof.

The broken lines depict environmental subject matter and form no part of the claimed design.

1 Claim, 8 Drawing Sheets---
